(57) **CLAIM**

We claim, the ornamental design for an ultrasonic catheter handpiece housing, as shown and described.

DESCRIPTION

This application is related to U.S. patent application Ser. Nos. 29/736,666 and 29/736,680, each filed on Jun. 2, 2020. FIG. 1 is a top perspective view of an ultrasonic catheter handpiece housing showing our new design;

FIG. 2 is a top view of the ultrasonic catheter handpiece housing of FIG. 1;

FIG. 3 is a bottom view of the ultrasonic catheter handpiece housing of FIG. 1;

FIG. 4 is a right side view of the ultrasonic catheter handpiece housing of FIG. 1;

FIG. 5 is a left side view of the ultrasonic catheter handpiece housing of FIG. 1;

FIG. 6 is a first end view of the ultrasonic catheter handpiece housing of FIG. 1; and,

FIG. 7 is a second end view of the ultrasonic catheter handpiece housing of FIG. 1.

The broken lines in the drawings illustrate portions of an ultrasonic catheter handpiece housing and form no part of the claimed design.
